PROCESS FOR PRODUCING OXYGEN

Paul W. Garbo, Freeport, N. Y., assignor to Hydrocarbon Research, Inc., New York, N. Y., a corporation of New Jersey

Application November 1, 1947, Serial No. 783,551

19 Claims. (Cl. 62—175.5)

1

This invention relates to the production of oxygen by the liquefaction and rectification of air, and more particularly to an economical method of obtaining oxygen in high purity and in high yield without the use of chemical reagents to effect the removal of carbon dioxide present in air.

All temperatures herein are in degrees F. and pressures in pounds per square inch gauge.

Oxygen is commonly produced by liquefaction of air and rectification at low temperatures; preferably rectification is conducted in two stages at different pressures. The refrigeration necessary for liquefaction is supplied to the air, after it has been compressed and water-cooled to approximately room temperature, by indirect heat exchange with the effluent products of rectification. However, an additional amount of refrigeration must be supplied to compensate for cold losses resulting from the difference in enthalpy between the incoming air and the outgoing products of rectification and for heat leaks into the system. Methods of supplying this refrigeration heretofore used involve compressing at least a portion of incoming air to pressures as high as 3000 pounds and expanding with or without the performance of work to produce a temperature drop; or compressing all the incoming air to about 600 pounds and after the air has been partially cooled by the products of rectification expanding a portion of the air. These methods are wasteful from the standpoint of compressor energy and require a great deal of equipment in the form of extra compressors, intercoolers and expanders.

For economical operation it is essential to recover the cold content of the outgoing products of rectification. This is usually accomplished by passing these products in heat transfer relationship with the incoming air. In older systems, in order to avoid deposition of frost and solid carbon dioxide in the tubular countercurrent heat exchangers through which the air is passed in indirect heat exchange relation with the outgoing products of rectification, the air is treated in driers and caustic scrubbers to remove water and carbon dioxide prior to admittance of the air into the heat exchangers. Even with this treatment the exchangers had to be thawed out regularly to remove the frost (which term is used in a generic sense to include both snow and ice) which caused stopping up of the apparatus.

More recently it has been suggested to use cold accumulators or regenerators (hereinafter referred to as heat exchangers) of large cold ab-

2

sorbing capacity through which the warm incoming air and the cold products of rectification are alternately passed with periodically reversed operation so that streams of warm air are flowed through the same packing-filled spaces that the cold separated oxygen and nitrogen traversed during the previous step in the process, the high boiling impurities deposited in these spaces during the passage of air therethrough being removed by sublimation during the subsequent flow in a reverse direction of the products of rectification. The use of these reversing heat exchangers in a process in which the air is compressed to relatively high pressure results in more costly operation from the standpoint of horsepower requirements because upon every reversal, which may take place every three minutes, the volume of compressed air in the heat exchangers is lost and must be again replaced. Moreover, in the operation of such reversing heat exchangers it is important not to let the temperature at the exit end of the exchangers drop to a point where a part of the air becomes liquid because this liquid adheres to the surface of the exchangers and is wasted upon reversal of flow.

Among the objects of this invention are to provide a process of producing oxygen by the liquefaction and rectification of air, in which the carbon dioxide and preferably also the moisture are removed from the air without the use of chemical reagents by flow through reversing heat exchangers of the regenerator or recuperator type, operated at relatively low pressures, of the order of about 60 to 100 pounds, so that the loss of compressed air in the exchangers upon each reversal is small; and the reversing exchangers are operated under conditions such that the carbon dioxide deposited therein is removed efficiently to permit substantially continuous operation of the process and notwithstanding the use of a rectification product stream to improve the efficiency of the carbon dioxide purging a portion of this rectification product stream may be withdrawn in substantially uncontaminated condition, i. e., not contaminated with condensable constituents removed from the air stream.

Other objects and advantages of this invention will be apparent from the following detailed description.

In accordance with this invention, a stream of rectification product is passed through a path in a heat exchange zone and a stream of air is passed through another path in this heat exchange zone. The air is thus cooled to a temperature close to its condensation point at the

pressure existing in the heat exchange zone thereby substantially completely removing all carbon dioxide present in the air. The flow of these two streams is periodically reversed so that the air flows through the path through which had previously flowed the rectification product and the rectification product flows through the path through which had previously flowed the air, the rectification product effecting the removal of carbon dioxide deposited in the heat exchange zone during the preceding step of the process. A non-reversing stream of rectification product preferably oxygen is passed through at least the cold end of the heat exchange zone where deposition of carbon dioxide takes place in indirect heat exchange relation with the air and the first mentioned stream of rectification product; this non-reversing stream of rectification product is thus warmed. A portion of this non-reversing stream of rectification product is withdrawn as product uncontaminated by carbon dioxide or other condensable constituents deposited in the heat exchange zone from the air stream passing therethrough. The remainder of this stream of rectification product is recirculated through its flow path in the heat exchange zone, augmented by additional rectification product from the rectification system.

By circulating a rectification product stream through a fixed path in at least the cold end of the heat exchange zone, the temperature conditions within this cold end are maintained such that efficient purging of this heat exchange zone takes place during each reversal period. Further, since the non-reversing rectification product stream flows through a fixed path through which the air never passes, efficient purging is effected without contaminating the non-reversing rectification product stream with air.

More specifically, in accordance with this invention a stream of air at about 60 to 100 pounds and at a temperature of about 70° to about 110° F. is passed through a heat exchange zone in heat exchange relation with a stream of nitrogen rectification product or oxygen rectification product or both nitrogen and oxygen rectification products and the flow of the air stream and the rectification product stream or streams periodically reversed so that the rectification product or products flow through the path through which had previously flowed the air and thereby effect removal of carbon dioxide deposited in the heat exchange zone during the preceding step of the process. In addition, a non-reversing stream of rectification product, preferably oxygen, is passed through at least the cold end of the heat exchange zone where deposition of carbon dioxide takes place in indirect heat exchange relation with the air and the other stream or streams of rectification product or products; this non-reversing stream of rectification product is thus warmed. A portion of this non-reversing stream of rectification product is withdrawn as product uncontaminated by carbon dioxide or other condensable constituents deposited in the heat exchange zone from the air stream passing therethrough. The remainder of this stream of rectification product is recirculated through its flow path in the heat exchange zone augmented by additional rectification product from the rectification system.

The stream of air leaves the heat exchange zone at a temperature below about -270° F. but above its condensation point. This stream is divided into two streams, one comprising the

major portion of the air flowing to the rectification system and the other comprising the remaining minor portion, say 15% to 35% by volume of the total air introduced into the process. The stream consisting of the minor portion of the air is warmed to a temperature such that upon subsequent expansion little or no liquid air is formed in the expander; the warming is preferably achieved by heat exchange with the non-reversing rectification product stream which is recirculated within the heat exchange zone. The non-reversing rectification product stream also desirably flows in heat exchange relation with a reversing rectification product stream, preferably nitrogen, to heat this stream to a temperature within 5° to 10° F., preferably 6° to 8° F., below the temperature of the exiting air stream, thereby conditioning the reversing rectification product stream so that it effects more efficient removal of carbon dioxide deposited in the exchanger during the preceding step of the process. The minor portion of the air stream which is warmed is then expanded to produce the refrigeration necessary to compensate for cold losses resulting from the difference in enthalpy between the incoming air and the outgoing products of rectification and for heat leaks into the system. The expanded air is introduced into the low pressure stage of the rectification system where its oxygen content is recovered. The low pressure stage is generally operated under a pressure of from about 5 to 12 pounds, preferably at about 7 to 9 pounds; the high pressure stage is maintained at a pressure of from about 60 to 100 pounds, preferably at about 75 to about 90 pounds. The remaining major portion of the air is also introduced into the rectification system where it is rectified to recover its oxygen content.

Thus when operating in accordance with this invention, the minor portion of the air which is to be expanded is first cooled to a temperature such as to effect the complete removal of carbon dioxide therefrom, permitting operation of the expander without encountering the troubles heretofore experienced because carbon dioxide solidified in the expander during the expansion of the air stream. The warming of the air stream before expansion to a temperature such that upon subsequent expansion little or no condensation or formation of liquid air in the expander takes place results in a further improvement in the operation of the expander. The warming of the reversing rectification product stream prior to its introduction into the heat exchange zone to a temperature within 5° to 10° F., preferably 6° to 8° F., of the exiting air stream results in satisfactory purging of the flow path through which this rectification product stream passes. Since the non-reversing rectification product stream flows through a flow path in the heat exchange zone through which the air never passes, it is not contaminated by carbon dioxide and other condensables removed from the air, and, hence, provides a relatively pure rectification product and at the same time efficiently supplies the heat necessary for warming (1) the air stream prior to its expansion to obtain the above noted improvements in the expander, and also (2) the reversing rectification product stream to obtain the above noted efficient periodic purging of the heat exchange zone.

In the accompanying drawings forming a part of this specification and showing, for purposes of exemplification, preferred layouts of equip-

ment for practicing the process of this invention. Figure 1 illustrates diagrammatically a preferred layout of apparatus for practicing the process of this invention; the apparatus of this figure involves heat exchangers of the recuperator type;

Figure 2 illustrates a modified arrangement of heat exchangers of the regenerator type which may be used in lieu of the exchangers of the recuperator type shown in Figure 1;

Figure 3 illustrates still another modified arrangement of exchangers of the regenerator type; and

Figure 4 illustrates still another modified arrangement of apparatus involving exchangers of the recuperator type for practicing the process of this invention.

It will be understood the drawings illustrate diagrammatically preferred apparatus for practicing this invention and that the invention may be carried out in other apparatus. For example, any desired number of reversing exchangers of either the recuperator or regenerator type may be used in lieu of the reversing exchangers shown in the drawings; each of the reversing exchangers of the drawings may be replaced by two or more similar exchangers placed in series and/or parallel, if desired; the divided or split exchangers hereinafter described may be disposed in a single housing or may be constructed as separate and distinct units; other rectification systems may be used in lieu of those shown in Figures 1 and 4 including rectification systems equipped with means for purging the high pressure stage to remove incondensable gases, such as helium, hydrogen and neon therefrom, or the rectification system of Figure 4 may be used with the exchangers of Figures 1, 2 and 3, or that of Figure 1 may be used with the exchangers of Figures 2, 3 and 4; the manner of providing refrigeration to compensate for cold losses resulting from the difference in enthalpy between the air introduced into and the products of rectification withdrawn from the process and for heat leaks into the system disclosed in Figure 1 may be employed with the exchangers shown in the other figures of the drawings, or conversely the manner of providing such refrigeration shown in Figure 4 may be used with the exchangers of the other figures of the drawings.

In the drawings, in which like reference characters indicate like parts, referring to Figure 1, 10 is a heat exchanger which may be of any well known type. In the embodiment shown in Figure 1 it consists of two sections 10a and 10b. Section 10a is provided with three flow paths, namely, interior path 11 and concentric paths 12 and 13 disposed in heat exchange relation with each other. The heat exchanger has in each of the paths suitable fins of heat conducting material, e. g., copper or aluminum, for promoting rapid and efficient heat exchange between the gaseous media flowing therethrough. For purposes of illustration and in the interests of simplicity each flow path in an exchanger is shown on the drawings as being formed of a single tube, the several paths being disposed concentrically. Actually, however, each path in each exchanger may comprise a multiplicity of tubes for flow therethrough. One form of the exchanger of the recuperator type, shown diagrammatically in Figures 1 and 4, which may be used in practicing the process of this invention is disclosed and claimed in application Serial No. 676,142, filed June 12, 1946. As the construction of the heat

exchanger per se does not form a part of this invention and as it may be of any well known type, it is believed further description thereof is unnecessary.

Exchanger section 10b has three flow paths 15, 16 and 17. Flow path 17 is connected with path 13 by line 18 and flow path 16 is connected with path 12 by line 19. Flow path 15 communicates with flow path 11 through a line 20 provided with a branch line 21, the function of which will be hereinafter described.

Paths 12 and 13 of section 10a and 16 and 17 of section 10b are the paths through which air and nitrogen flow, the flows of these two media through their respective paths being periodically reversed so that during one step of the process air flows through paths 12 and 16 and nitrogen flows through paths 17 and 13 and upon reversal during the succeeding step air flows through paths 13 and 17 and nitrogen through paths 16 and 12. Reversal of flow is accomplished by suitably positioning compound reversing valves 22, 23 which may be of any well known type. Valve 22 is disposed in a pipe line system consisting of (a) air inlet pipe 24 leading into valve 22, (b) nitrogen exit line 25 leading to any suitable point of nitrogen disposal, and (c) lines 26 and 27 communicating with paths 12 and 13, respectively, as shown in Figure 1. Lines 28 and 29 lead from the flow paths 16 and 17 to valve 23. Nitrogen inlet line 30 leads into valve 23, and this valve is provided with an air exit line 31.

Flow path 15 is provided with an oxygen inlet line 32, the oxygen flows through path 15, thence into line 20; a portion is withdrawn through branch line 21 and the remainder passes through flow path 11 into an oxygen exit line 33. No reversal of flow of the oxygen relative to the gaseous streams passing through the exchanger 10 takes place.

The rectification system of Figure 1 comprises a two-stage rectification column 34, the lower section 35 of which is operated at a pressure of about 60 pounds to about 100 pounds, preferably about 75 to 90 pounds, and the upper section 36 of which is operated at a pressure of from about 5 pounds to about 12 pounds, preferably at about 7 to 9 pounds. This column, as is customary, is provided with rectification plates of the bubble cap or other desired type. The lower section 35 communicates with a condenser 37 and has a liquid collecting shelf 38 disposed immediately below the condenser for collecting liquid nitrogen. Pipe line 39 leads from shelf 38 to a non-reversing heat exchanger 40 which communicates through a pressure reducing valve 41 with the top portion of the low pressure stage 36. Condenser 37 acts as a reboiler for the upper section 36.

From the base of the lower section 35 a pipe line 42 for the flow of crude oxygen passes to a non-reversing heat exchanger 43 which communicates through pipe line 44 having a pressure reducing valve 45 therein with the low pressure section 36 at an intermediate point 46. A line 47 having a pressure reducing valve 48 therein leads from condenser 37 to a nitrogen line 49. A line 50 leads from the top of the low pressure section 36, passes through heat exchangers 40 and 43 and enters line 49; the nitrogen stream flowing through line 50 enters line 49 where it joins the stream from line 47. Nitrogen line 49 enters a non-reversing heat exchanger 51 which has a nitrogen exit line 52 leading into a non-reversing heat exchanger 53 provided with a

nitrogen exit line 54 communicating with line 30 entering valve 23. A by-pass line 55 provided with a valve 56 therein by-passes the exchanger 53 so that more or less of the nitrogen flowing through line 52 and depending upon the position of valve 56 may be caused to by-pass the heat exchanger 53, thereby controlling the temperature of the nitrogen entering the valve 23.

An oxygen line 57 leads from the low pressure section 36 to line 32 which leads into flow path 15 of section 10b.

Branch line 21 communicates with a pump or blower 60 for pumping the oxygen flowing through branch 21 through a line 61 leading into a non-reversing exchanger 62. From the non-reversing exchanger 62 a line 63 leads into and through the non-reversing exchanger 53, line 63 communicating with the oxygen line 32 at 64.

Air line 31 is provided with a branch 65 having a valve 66 therein which leads into and through the exchanger 62, thence through line 67 into an expander 68 from which a line 69 leads into the low pressure section 36 of rectification column 34. A by-pass line 70 having a valve 71 therein extends from the air line 31 to line 67 leading into the expander 68. More or less of the air entering the expander 68 depending upon the setting of the valves 66 and 71 may thus be by-passed about the exchanger 62, thereby controlling the temperature of the air entering the expander 68. Air line 31 extends through the non-reversing heat exchanger 51 and enters the high pressure stage of the rectification column 34 at 72.

In operation of the equipment of Figure 1, air from the main air line 24 flows through valve 22, line 26, path 12, line 19, path 16, line 28, valve 23, line 31. In its flow through path 12 the air is cooled to a temperature sufficient to remove all moisture, if any, present in the air. In its flow through path 16 the air is cooled to a temperature near its condensation point, so that all carbon dioxide is removed therefrom and deposited in the flow path 16. The major portion of the air leaving path 16 flows through line 31, non-reversing exchanger 51 into the high pressure stage of the rectification system at 72. The remaining minor portion flows through lines 65 and 70, that flowing through 65 passing in indirect heat exchange relation with warm oxygen flowing through exchanger 62, whereby the air is warmed. The thus warmed air mixes in line 67 with the air flowing through line 70 to produce a mixture at a desired temperature such that upon expansion no liquid air is formed in expander 68. The expanded air from expander 68 flows through line 69 and enters low pressure stage 36 of the rectification column 34.

Nitrogen flows from the low pressure stage 36 through line 50 and a minor nitrogen stream vented from the condenser 37 in order to purge helium and other incondensable gases flows through line 47, both streams entering line 49. The resultant nitrogen stream passes through non-reversing heat exchanger 51, into and through line 52 from which at least a portion of the nitrogen passes through the non-reversing heat exchanger 53 where it flows in heat exchange relation with the warmed oxygen stream passing through this exchanger. From this exchanger the warmed nitrogen flows through line 54 into line 30 entering valve 23. If desired, a portion of the nitrogen stream from line 52, the amount depending on the setting of valve 56, flows through line 55 by-passing exchanger 53 and mixes in line 30 with the warmed nitrogen which

has passed through exchanger 53; thus the temperature of the nitrogen stream entering valve 23 is controlled so that the nitrogen enters at a temperature at which it will effect efficient purging of the flow paths in exchangers 10b and 10a through which it flows. From valve 23 the nitrogen stream during one cycle flows through line 28, path 17, line 18, path 13, line 27, valve 22 into nitrogen exit line 25.

Oxygen flows through lines 51 and 32 into and through flow path 15. In its flow through this flow path the oxygen is warmed by indirect heat transfer with the air stream flowing through the exchanger. The oxygen leaves path 15 through line 20. A portion of the oxygen from line 21 is returned by blow 60 through the non-reversing heat exchanger 62 where it gives up some of its heat to the air stream passing through this exchanger to warm this air stream. From exchanger 62 the oxygen flows through line 63 into and through exchanger 53 where, as above described, it gives up additional heat to the nitrogen stream flowing through this exchanger. The recirculating oxygen stream then enters oxygen line 32 mixing with the oxygen stream flowing from the rectification column 34; the resultant oxygen stream enters path 15 through line 32. The remainder of the oxygen stream not recirculated by blower 60 through the exchangers 62 and 53 flows from line 20 through path 11 of exchanger 10a and is withdrawn as product oxygen through the exit line 33.

Upon reversal, as indicated by the dotted setting of reversing valves 22 and 23, which reversal 35 may take place every three minutes, air flows through line 24, line 27, flow path 13, line 18, flow path 17, line 29, valve 23 into line 31. The major portion of the air from line 31 flows through heat exchanger 51 into the high pressure 40 stage 35 of the rectification column 34. The remaining minor portion flows as hereinabove described so that it is warmed by the recirculating oxygen stream passing through exchanger 62 and is thus warmed before expansion in expander 68, 45 the expander air flowing through line 69 into the low pressure stage 36 of the rectification column 34. Nitrogen enters valve 23 through the same flow system as hereinabove described and flows through line 28, path 16, line 19, path 12, line 26, valve 22 to the nitrogen exit line 25. Oxygen flows through line 32, path 15, a portion of the oxygen from line 20 being recirculated by blower 60 through heat exchanger 62, line 63, heat exchanger 53, line 32, back to the flow path 55 15, the remainder passing through path 11 to the oxygen exit line 33.

Thus, it will be noted that flow through the flow paths 15 and 11 always takes place in the same direction throughout the operation of the process. On the other hand, flow of the nitrogen and air through their respective flow paths is periodically reversed, the nitrogen on each reversal flowing through the path through which had previously passed the air and removing from this path carbon dioxide and other condensibles removed from the air stream during the preceding step of the process. Since the oxygen stream employed to condition the nitrogen stream to effect more efficient purging flows through a path in the exchanger through which air never passes, it is not contaminated by condensibles removed from the air stream.

The exchanger system of Figure 2 differs from that of Figure 1 chiefly in that (1) the exchangers of Figure 2 are of the regenerator type and

(2) the recirculating oxygen stream flows through the entire length of the exchangers, whereas in Figure 1 the recirculating oxygen stream flows through section 10b only and not through section 10a.

In Figure 2, 75, 76 are a pair of regenerators each containing material, such as copper or aluminum, of high heat transfer capacity over which flow alternately streams of rectification product and air, the rectification product imparting its cold content to this material and the air recovering this cold when it flows thereover during the succeeding step of the process, as is well known in this art. Extending through the regenerators 75, 76 are oxygen flow paths 77, 78, respectively. Each of these flow paths desirably is in the form of one or more tubes of high heat conducting material, such as copper or aluminum; the oxygen passing therethrough is in indirect heat exchange relationship with the material of high heat transfer capacity in the regenerators 75, 76. Path 77 is connected with oxygen line 32 by a line 79 and path 78 is connected with oxygen line 32 by a line 81. The exit ends of these oxygen flow paths 77 and 78 lead into lines 83 and 84, respectively, which in turn communicate with an oxygen line 85 provided with a branch 86. As in the modification of Figure 1 a blower 60 may be disposed in the branch 86 for recirculating a portion of the oxygen flowing through line 85 through non-reversing heat exchangers 62 and 53 into the oxygen line 32 where the recirculated oxygen mixes with the stream of oxygen flowing from the rectification system, the resultant oxygen stream flowing through the flow paths 77 and 78.

Reversing valve 22 is provided with a line 87 leading into the regenerator 75 and a second line 28 connecting this valve with regenerator 76. The other reversing valve 23 is provided with a pair of lines 89 and 90 connecting this valve with regenerators 75 and 76, respectively. By means of these reversing valves the flow of air is caused to take place alternately through regenerators 75, 76 and the flow of nitrogen alternately through the regenerators 76 and 75 so that during each stem air flows through one regenerator and nitrogen through the other and upon reversal the air flows through the regenerator through which had previously flowed the nitrogen and the nitrogen flows through the regenerator through which had previously flowed the air.

In the operation of the modification of Figure 2 air at a pressure of 60 to 100 pounds and a temperature of from 70° to 110° F. supplied through line 24 flows through valve 22, line 88 into and through the regenerator 76 where it is cooled to a temperature close to its condensation point at the pressure prevailing in this regenerator. The thus cooled air exits through line 90 into valve 23 from which the air flows through line 31 to the rectification system as hereinabove described in connection with the description of Figure 1. Simultaneously, nitrogen flows through line 30, valve 23, line 89 into and through the regenerator 75 giving up its cold to the heat transfer material in regenerator 75. The thus warmed nitrogen stream exits through line 87, valve 22 and nitrogen exit line 25. Oxygen from the rectification system flows through line 32, lines 79, 81, oxygen flow paths 77, 78, lines 83, 84 into the oxygen line 85. A portion of this oxygen is withdrawn as product and the remainder recirculated by blower 60 through line 76

86 into line 61 and ultimately into the oxygen supply line 32 from which the recirculated oxygen augmented by oxygen from the rectification system flows through lines 79, 81 into the oxygen flow paths 77, 78.

Upon reversal which may take place every three minutes, as indicated by the dotted line valve settings, air flows through valve 22, line 87 into and through the regenerator 75 and is refrigerated to a temperature close to its condensation point in its flow through this regenerator. The air exits through line 89 flowing into and through valve 23 into line 31 from which the air flows through the same lines as hereinabove described in connection with the description of Figure 1. Simultaneously, nitrogen flows from line 30 through valve 23, line 90 into and through the regenerator 76, line 88, valve 22 and exits through the nitrogen exit line 25. Oxygen flows through the same paths as during the preceding step of the process; namely, through the oxygen flow paths 77 and 78 countercurrent to the stream of air flowing through one of the regenerators 75, 76 and cocurrent with the stream of nitrogen flowing through the other regenerator in indirect heat exchange relationship therewith.

The nitrogen which alternately flows through one or the other of the regenerators 75 and 76 removes therefrom carbon dioxide and other condensibles deposited therein during the preceding step of the process. The efficiency of the purging action of the nitrogen is materially improved by the recirculated stream of oxygen, which stream of oxygen results in temperature conditions within the regenerators optimum for effecting removal of carbon dioxide by the nitrogen stream flowing therethrough.

The modification of Figure 3 may be used with a rectification system such as disclosed in Figure 40 1 or 4. This modification differs from that of Figure 2 chiefly in four respects, i. e.,

1. Two sets of regenerators are used instead of a single set, one set being employed for the alternate flow of oxygen and air therethrough and the other set for the alternate flow of nitrogen and air.

2. The regenerators of each set are split or divided into two sections.

3. Nitrogen rectification product instead of oxygen is recirculated through flow paths in the regenerators in indirect heat exchange relationship with the gaseous media flowing therethrough.

4. The recirculated nitrogen stream, as in the modification of Figure 1, is passed through a portion only of the extent of each regenerator set, and a portion of the nitrogen is withdrawn as product uncontaminated by condensable constituents removed from the air.

In Figure 3 the two sets of regenerators are indicated by A and B. In the embodiment shown on the drawing set A comprises one regenerator consisting of sections 91, 92 connected by a line 93 and a second regenerator consisting of sections 94 and 95 connected by a line 96. The regenerators of set A are for alternate flow of air and nitrogen therethrough. Set B comprises one regenerator consisting of sections 97, 98 connected by a line 99 and a second regenerator consisting of sections 100, 101 connected by a line 102. The regenerators of set B are for alternate flow of air and oxygen therethrough and desirably are of approximately one-fourth the volumetric capacity of the regenerators of set A. Sections 91 and 92 have nitrogen flow paths 103, 104 passing therethrough and interconnected by a line 105. Simi-

11

lary sections 94 and 95 have nitrogen flow paths 106, 107 passing therethrough and interconnected by a line 108. Section 98 has a nitrogen flow path 109 and section 101 a nitrogen flow path 110 passing therethrough and leading into lines 111 and 112, respectively. Lines 111 and 112 communicate with a line 113 which is also connected with lines 105 and 108. Except as above noted the regenerators of sets A and B are constructed the same as the regenerators of Figure 2.

Reversal of flow through the regenerators of set A is accomplished by a pair of reversing valves 114 and 115. Valve 114 is connected with regenerator section 91 by a line 116 and with regenerator section 94 by a line 117. Air line 118 is provided with a branch 119 which leads into valve 114. A nitrogen exit line 120 leads from the valve 114. Reversing valve 115 is connected with regenerator sections 92 and 95 by lines 121 and 122, respectively. A nitrogen line 123 leads from the rectification system into the reversing valve 115. Air line 124 leads from reversing valve 115 to the rectification system.

Reversal of flow through the regenerators of set B is accomplished by a pair of reversing valves 125 and 126. Valve 125 is connected with regenerator sections 97 and 100 by lines 127 and 128. A line 129 leads from the main air line 118 to valve 125; an oxygen exit line 130 leads from this valve. Valve 126 is connected with regenerator sections 98 and 101 by lines 131 and 132, respectively. Oxygen line 133 communicates with valve 126. Air line 124 is provided with a branch leading from valve 126.

A branch line 135 leads from the nitrogen line 123 to the lines 136, 137, 138 and 139 communicating with nitrogen flow paths 104, 107, 109 and 110, respectively. Nitrogen flow paths 103 and 106 are provided with nitrogen exit lines 140 and 141 leading into a nitrogen product line 142. Line 113 which receives the nitrogen recirculated through the flow paths 104, 107, 109 and 110 communicates through a line 143 with branch line 135 thus completing the circulating system for the recirculated nitrogen, which system consists of the nitrogen branch line 135 connecting lines 136, 137, 138 and 139, nitrogen flow paths 104, 107, 109 and 110, nitrogen exit lines 105, 108, 111 and 112, line 113, connecting line 143 and a pump 144 in line 143 for effecting the recirculation of the nitrogen through this circulating system. Heat exchangers may be disposed in line 143 as shown in Figure 1 in connection with line 61.

In the operation of the modification of Figure 3 air is admitted through line 118 to valves 114 and 125 and flows through regenerator sections 94 and 100 then through connecting lines 96, 102 into and through regenerator sections 95 and 101 into and through the lines 122 and 132 through the valves 115 and 126 into the air line 124. Simultaneously, oxygen flows through line 133, valve 126, line 131, regenerator section 98 through the connecting line 99 into and through regenerator section 97, line 127 into valve 125 and exits through the oxygen exit line 130. Nitrogen flows through line 123, valve 115, line 121, regenerator section 92, line 93, regenerator section 91, line 116, valve 114 exiting through the exit line 120. Nitrogen also flows through line 135, branches 136, 137, 138 and 139 into and through the flow paths 104, 107, 109 and 110 in regenerator sections 92, 95, 98 and 101, respectively. From the flow paths 109 and 110 the nitrogen flows through lines 111 and 112 into line 113. From the flow paths 104 and 107 the nitrogen flows into lines

12

105 and 108, respectively, connected with line 113. Part of the nitrogen from line 113 is recirculated by pump 144 through line 143 into line 135 where it mixes with the nitrogen entering line 135 from line 123. The resultant mixed nitrogen stream, as hereinbefore described, flows through the flow paths 104, 107, 109 and 110. The remainder of the nitrogen in line 113 flows through lines 105 and 108 and flow paths 103 and 106 in the regenerator sections 91 and 94 and exits from these flow paths through lines 140 and 141 entering the nitrogen exit line 142 from which the nitrogen uncontaminated with condensibles removed from the air stream is withdrawn as product.

The relative proportions of nitrogen flowing through regenerators A and that flowing through the flow paths within these regenerators may be varied as desired. For example, from 70% to 90% by volume of the nitrogen rectification product may be passed through regenerator A to effect purging and the rest passed through the flow paths.

Upon reversal, which may take place every 25 three minutes, as indicated by the dotted line valve settings, air flows through regenerator sections 91 and 97, thence through the regenerator sections 92 and 98, through the communicating lines 121 and 131 into and through valves 115 and 128 and into the air line 124. Simultaneously, oxygen flows from line 133, through valve 126, line 132, regenerator section 101, line 102, regenerator section 100, line 128, valve 125, into and through the oxygen exit line 130. The oxygen in its flow through the regenerator sections 100 and 101 removes therefrom carbon dioxide and other condensibles deposited therein by the air in its flow through these regenerator sections during the preceding step of the process. 40 Nitrogen flows from line 123 through valve 115, line 122 and regenerator sections 95 and 94, line 117, valve 114 into nitrogen exit line 120. This nitrogen stream removes from regenerator sections 95 and 94 carbon dioxide, frost and other condensibles deposited therein by the air stream flowing therethrough during the preceding step of the process. Nitrogen also flows through line 135, connecting lines 136, 137, 138 and 139 into the nitrogen flow paths 104, 107, 109 and 110 and 45 thence through lines 105, 108, 111 and 112, respectively into line 113. As hereinabove described, a portion of the nitrogen in line 113 is recirculated by pump or blower 144 through the nitrogen flow paths and the remainder flows through lines 105 and 108, through the flow paths 103 and 106 in regenerator sections 91 and 94 into the nitrogen exit lines 140 and 141 leading into line 142 from which the nitrogen rectification product is withdrawn uncontaminated by 50 carbon dioxide and other condensibles removed from the air stream passing through these regenerators.

The nitrogen flowing through line 113 to the line 135 may, if desired, be passed in heat exchange relationship with a minor portion of the air stream withdrawn from line 124 to supply heat to this minor portion of the air stream prior to expanding same in a manner corresponding to the flow of the recirculating stream passing 55 through exchanger 62 in the modification of Figure 1. Alternatively, the recirculating nitrogen stream may pass through a refrigeration system, as hereinafter described in connection with the modification of Figure 4, refrigeration being supplied thereto in amount adequate to compensate

for cold losses resulting from the difference in enthalpy between the air introduced into and the products of rectification withdrawn from the process and for heat leaks into the system. The regenerator system of Figure 3 may be operated with a portion of the oxygen rectification product stream recirculated, as shown with the recuperators of Figure 4, through the flow paths in the exchangers instead of recirculating a portion of the nitrogen rectification product, as hereinabove described.

The modification of Figure 4 differs from that of Figure 1 chiefly in that

(1) two sets of exchangers of the recuperator type, one for the reversal of air and nitrogen and the other for the reversal of air and oxygen are used;

(2) refrigeration to compensate for cold losses resulting from the difference in enthalpy between the air introduced into and the products of rectification withdrawn from the process and for heat leaks into the system is supplied by a refrigeration system and not by expanding a minor portion of the air, as in the modification of Figure 1; and

(3) a two-column rectification system is used in lieu of the unitary column shown in Figure 1.

In Figure 4 reference characters C and D indicate two sets of heat exchangers of the recuperator type; C is the heat exchanger in which flow of air and nitrogen is reversed, and D is the exchanger in which the flow of air and oxygen is reversed. In general these exchangers are of substantially the same design and construction as the exchanger 10 of Figure 1. Exchanger D is of approximately one-fourth the volumetric capacity of exchanger C. The latter exchanger comprises two sections, 148, 149; section 148 consists of two flow paths 150 and 151 connected by lines 152 and 153 with the flow paths 154 and 155 of the section 149. Section 149 comprises a third flow path 156 for the flow of oxygen therethrough. Exchanger D comprises two sections 157 and 158. Section 157 is provided with three flow paths 159, 160 and 161 and section 158 is also provided with three flow paths 162, 163 and 164. Flow paths 159 and 162 are connected by a line 165; flow paths 160 and 163 are connected by a line 166 and flow paths 161 and 164 are connected by a line 167.

Reversal of flow through exchanger C is effected by a pair of reversing valves 168 and 169. Valve 168 is connected with flow paths 150 and 151 by lines 170 and 171. Air line 172 has one branch 173 leading into valve 168 and this valve is provided with a nitrogen exit line 174. Valve 169 is connected with flow paths 154 and 155 by lines 175 and 176. Valve 169 has a nitrogen line 177 leading thereto and is provided with an air exit line 178.

Reversal of flow through the exchanger D is effected by a pair of reversing valves 179 and 180. Valve 179 is connected with flow paths 159 and 160 by means of lines 181 and 182. Valve 179 has a branch line 183 leading thereto from the air line 172. This valve is also provided with an oxygen discharge line 184. Valve 180 is connected with flow paths 162 and 163 by lines 185 and 186. This valve has leading thereto an air line 187; an oxygen supply line 188 leads into this valve.

The rectification system comprises two columns 200 and 201. Column 200 is operated at a pressure of from about 60 pounds to about

100 pounds, preferably at about 75 pounds to 90 pounds, and column 201 at a pressure of from about 5 pounds to about 12 pounds, preferably at about 7 to 9 pounds. These columns, as customary, are provided with rectification plates of the bubble-cap or other desired type. Air is supplied to the base portion of the high pressure column 200 through an air line 202 into which lead the lines 178 and 187, and which passes through non-reversing heat exchangers 203 and 204 hereinafter more fully described. Crude oxygen containing approximately 40% oxygen, the rest being chiefly nitrogen, flows from the base of column 200 through line 205 which passes through a non-reversing heat exchanger 206. Upon flow through an expansion valve 207 in line 205 crude oxygen is flashed entering column 201 at 208. Line 209 leads from the top of column 200, passes through a non-reversing heat exchanger 210 into a line having one branch 211 for returning liquid reflux comprising chiefly nitrogen to column 200, and another branch 212 passing through a non-reversing heat exchanger 213 and leading into the low pressure column 201 at 214. An expansion valve 215 is disposed in the branch 212.

The base of column 201 is provided with a line 216 passing through the non-reversing heat exchanger 210, this line having a return portion 217 leading into the low pressure column 201 at its base. The lines 216 and 217 and the cooperating heat exchanger 210 function as a reboiler; liquid oxygen flows through line 216 through exchanger 210 in indirect heat exchange relation with the gaseous stream comprising chiefly nitrogen passing through line 209 which causes vaporization of the liquid oxygen to take place, the oxygen vapors flowing into column 201 through line 217. A nitrogen line 218 leads from the top of column 201, passes through exchangers 213, 206, 204 and 219 and communicates with line 177 leading to the reversing valve 169. An oxygen line 220 leads from the base of column 201, passes through the exchanger 203 and communicates with the oxygen line 188 leading to the reversing valve 168.

Oxygen flow path 156 is provided with an exit line 221 leading into a line 222 which communicates with line 167 connecting oxygen flow paths 164 and 161. A pump 223 is disposed in line 222. This line passes through a refrigeration system 224, which may be of any well known construction for supplying a refrigerating medium, such as ethylene or methane to cool the recirculating oxygen stream flowing therethrough. This refrigerating system operates to cause the flow of the refrigerating medium in indirect heat exchange relation with the oxygen, the rate of flow and the temperature of the various media being so controlled that enough cold is introduced by refrigeration at this point in the process to compensate for cold losses resulting from the difference in enthalpy between the incoming air and the outgoing products of rectification and for heat leaks into the system. From the refrigeration system 224 the oxygen line 222 passes through the non-reversing heat exchanger 219 into a line 225. An oxygen line 226 having therein a valve 227 connects the main oxygen line 188 with line 225. This line 225 is provided with branches 228 and 229 leading into the oxygen flow paths 156 and 164, respectively. Flow path 161 is provided with an oxygen exit line 230.

In the operation of the modification of Figure

15

4 air from the main air line 172 is divided into two streams, one of which flows through line 173, valve 168, line 170, flow path 150, line 152, flow path 154, line 175, valve 169, line 178 into the air line 202, and the other of which flows through line 183, valve 179, line 181, flow path 159, line 165, flow path 162, line 185, valve 180, line 187 into the air line 202. The air stream is thus cooled to a temperature near its condensation point and all carbon dioxide and moisture, if any, removed therefrom, the carbon dioxide being deposited in the flow paths 154 and 162 and the moisture, if any, in the flow paths 150 and 159. The air from line 202 flows through the heat exchanger 203 in heat exchange relation with oxygen passing through this exchanger, and also through exchanger 204 in heat exchange relation with the nitrogen passing through this exchanger and then into the high pressure column 200.

Nitrogen flows from the rectification system through line 218 passing through heat exchangers 213, 206, 204, 219 into line 171, valve 169, line 176, flow path 155, line 153, flow path 151, line 171, valve 168 to the nitrogen exit line 174. Simultaneously, oxygen flows from the rectification system through line 220, heat exchanger 203, a portion of the oxygen stream depending upon the setting of valve 227 flowing through line 226 into line 225 and the remaining major portion flowing through line 188, valve 180, line 186, flow path 163, line 166, flow path 160, line 182, valve 179 into and through the oxygen exit line 184. The portion of the oxygen passing through line 226 flows through line 225 where it mixes with the recirculating oxygen, the oxygen mixture passing through the branch lines 228 and 229 into and through the oxygen flow paths 156 and 164 into the lines 221 and 167, respectively, both of which communicate with line 222. Part of the oxygen in line 222 is pumped by pump 223 through the refrigeration system 224, heat exchanger 219 and enters line 225 where it mixes as hereinabove described with the oxygen entering this line through line 226. The resultant oxygen stream is recirculated through the flow paths 156 and 164. The remainder of the oxygen in line 222 flows through line 167, through the flow path 161 from which it is withdrawn through the oxygen exit line 230 as product uncontaminated by condensibles including carbon dioxide removed from the air stream.

Upon reversal, which may take place every three minutes, the air flows, in the case of the exchanger C, through valve 168, line 171, flow path 151, line 153, flow path 155, line 176, valve 169 into line 178 thence to line 202. In the case of exchanger D the air flow is through line 183, valve 179, line 182, flow path 160, line 166, flow path 163, line 186, valve 180, line 187, and thence to line 202 from which the flow is the same as hereinabove described in connection with the preceding step. Nitrogen flows from line 171 into valve 169, line 175, flow path 154, line 152, flow path 150, line 170, valve 168, thence through the nitrogen exit line 174. Oxygen flows through the recirculation system consisting of flow paths 156 and 164, lines 221 and 167, pump 223, refrigerating system 224, heat exchanger 219, lines 225, 228 and 229, the same as hereinabove described. Also a portion of the oxygen to be withdrawn as product flows through flow path 161 as hereinabove described in connection with the preceding step of the process. In addition a major portion of the oxygen flowing through line 220 flows

5 through line 188 from which it flows through valve 180, line 185, flow path 162, line 165, flow path 159, line 181, valve 179 into and through the oxygen exit line 184. The nitrogen, the flow of which is periodically reversed, in flow paths 154, 155 in exchanger 149 and flow paths 150 and 151 in exchanger 148 and the oxygen, the flow of which is periodically reversed, in flow paths 162, 163 in exchanger 158 and 159 and 160 in exchanger 157 remove from their respective flow paths the carbon dioxide and other condensibles deposited therein from the air stream flowing therethrough during the preceding step of the process. The oxygen stream withdrawn as product flowing through flow path 161, since it flows through a path through which the air never passes, is uncontaminated by condensibles removed from the air stream.

20 One example of the operation of the process of this invention in the apparatus shown in Figure 1 is described below. It will be understood this example is given for purposes of exemplification only and the invention is not limited thereto. The example refers to an oxygen plant operating in a locality where the atmospheric pressure is 14.6 pounds per square inch absolute.

25 Air, which has not been pretreated to remove moisture and which is compressed to a pressure of about 89.5 pounds, is supplied at a temperature of 90° F. through line 24, valve 22, line 26 to the flow path 12. The air leaves flow path 12 at a temperature of -125° F. and proceeds through line 19, flow path 16, line 28, valve 23 and line 31. The air leaves the flow path 16 at a temperature of -273° F.

30 Approximately 21% of the total air introduced into the process is expanded in expander 68. This fraction, which is to be expanded, flows through line 65 at a temperature of -273° F., entering 35 and flowing through heat exchanger 62, the air being thus heated to a temperature of -239.5° F.; line 70 provides a by-pass around exchanger 62 through which part of the air may be passed to control the temperature of the air entering expander 68. Under normal operating conditions, by-pass 70 is closed. In expander 68 the air is expanded to a pressure of about 8.5 pounds, its temperature thus being reduced to -303° F., at which temperature and pressure it is introduced into the low pressure stage 36.

40 The remainder of the air (approximately 79%) at a temperature of -273° F. flows through line 31 into heat exchanger 51 in heat exchange relation with the nitrogen stream flowing through line 49 at a temperature of -294.5° F. and undergoes partial liquefaction (about 1% being liquefied) and passes at a temperature of -275° F. and a pressure of about 86 pounds into the high pressure stage 35 at 12. The nitrogen flowing through heat exchanger 51 is thus warmed to a temperature of -292° F.

45 The nitrogen stream at this temperature of -292° F. flows through line 54 and heat exchanger 53 leaving this exchanger at a temperature of about -281° F.; by-pass 55 is closed under normal operating conditions. The nitrogen stream at a temperature of about -281° F. passes through line 30, valve 23, line 29 into flow path 17 of heat exchanger section 10b. Thus the temperature differential between the entering nitrogen stream and the exiting air stream at the colder end of exchanger section 10b is 8° F. The nitrogen leaves flow path 17 at a temperature of 50 -136° F. and passes through flow path 13, leav-

ing this flow path at a temperature of 80° F. and at substantially atmospheric pressure.

Oxygen at a temperature of -289° F. and a pressure of 8.8 pounds flows into line 32 where it mixes with the recirculated oxygen stream at a temperature of about -289° F. introduced into line 32 at 64. The mixed oxygen stream flows through path 15. About 36% of the oxygen which leaves path 15 at a temperature of -137.5° F. is returned by blower 60 through heat exchanger 62 where it is cooled to a temperature of about -218° F. and then through heat exchanger 53 where it is cooled to a temperature of -289° F., at which temperature it mixes with the oxygen flowing through line 32. The remainder of the oxygen flowing through line 20 continues through flow path 11, leaving this path at a temperature of 79.5° F. and at substantially atmospheric pressure. The stream exiting from line 33 contains approximately 96% by volume of oxygen.

In the operation of the rectification system 34, crude oxygen at a temperature of -275.5° F. and a pressure of about 86 pounds passes through line 42 through heat exchanger 43 in indirect heat exchange relation with nitrogen flowing through line 50. The crude oxygen is thus cooled to a temperature of -278° F. The crude oxygen is then flashed in its flow through expansion valve 45 entering section 36 as a vapor-liquid mixture at a temperature of about -306° F. and a pressure of about 8 pounds. Nitrogen at a temperature of -314° F. and a pressure of about 7 pounds flows through line 50 into heat exchanger 40 where it is warmed to a temperature of -297° F. by indirect heat exchange with the nitrogen reflux stream flowing through line 39. The nitrogen at a temperature of -297° F. flows through exchanger 43 where it is warmed to a temperature of -294.5° F. at which temperature it enters exchanger 51 by way of line 49 in which it mixes with purge nitrogen flowing through line 47. The nitrogen stream leaves exchanger 51 at a temperature of about -292° F., passes through exchanger 53 and flows into line 30 at a temperature of -281° F.

Oxygen at a temperature of -289° F. and a pressure of 8.8 pounds flows through line 57 into line 32 wherein it mixes with the recirculating oxygen stream hereinabove described at a temperature at its point of mixing of -289° F. The resultant oxygen stream at a temperature of -289° F. as hereinabove described enters flow path 15. For every 100 volumes of oxygen entering line 32 by way of line 57, about 62 volumes of recirculated oxygen are mixed therewith at the point 64 in line 32. This recirculation corresponds to about 13 volumes per 100 volumes of air entering the process, all volumes being measured under standard conditions.

Upon reversal, which may take place every three minutes, the air flows through paths 13 and 17, nitrogen through paths 16 and 12, and the oxygen continues to flow through paths 15 and 11. The flow of the various streams is otherwise substantially the same as hereinabove described and the temperature and pressure conditions remain the same. The nitrogen in its flow through paths 16 and 12 removes by sublimation and evaporation the carbon dioxide and frost, if any, deposited in these paths by the air during the preceding step. Thus in the continued operation upon each reversal the nitrogen rectification product effects removal of the carbon dioxide and frost, if any, deposited in the paths

through which the air had passed during the preceding step of the process.

In the operation of the process of this invention it is preferred to effect removal of moisture and carbon dioxide both in accordance with the process of this invention. It will be understood, however, that if desired, the moisture may be removed from the air by any conventional means and dry air containing carbon dioxide passed through the exchanger or exchangers as hereinabove disclosed. In the event that dry air is supplied to the process and the exchanger system is similar to that of Figure 1, reversing valve 22 may advantageously be moved to the position 15 between exchangers 10a and 10b, so that reversal of the air and nitrogen streams occurs only in exchanger 10b, wherein the carbon dioxide is deposited by the air stream. The reversing valves 168 and 179 of Figure 4 may be 20 similarly positioned when the equipment of this figure is operated with dry air. Operating with dry air in equipment of the type shown in Figure 3 the reversing valves 114 and 125 may be placed at the warmer ends of regenerator sections 25 92, 95, 98 and 101, and the regenerator sections 91 and 94, and 97 and 100 replaced with two non-reversing exchangers of the recuperative type. Operation of such arrangements is 30 carried out so that the temperature at the warm end of exchangers 10b of Figure 1, 92, 95, 98 and 101 of Figure 3, 149 and 158 of Figure 4, is at least slightly higher than the temperature at which the carbon dioxide begins to deposit from the air stream. In general, the air entering the 35 warm end of these exchangers should be at a temperature in the range of about -110° to -160° F., the exiting product streams being about 10° to 15° F. colder.

As a desirable operating range the air is admitted to the inlet of the exchangers at a temperature of from 70° to 110° F. and a pressure of 60 to 100 pounds, preferably 75 to 90 pounds. The air in its flow through exchanger section 10a of Figure 1, 148 and 157 of Figure 4, or regenerator sections 91, 94, 97 and 100 of Figure 3, is cooled to a temperature of about -110° to -160° F. and at this temperature enters, respectively, exchanger section 10b of Figure 1, 149 and 158 of Figure 4, or regenerator sections 92, 95, 98 and 101 of Figure 3, exiting therefrom at a temperature within the range of -260° to -280° F. In general the oxygen rectification product enters the exchangers at a temperature of from -288° to -293° F., the nitrogen enters 55 at a temperature of from -265° to -285° F., and both the oxygen and nitrogen leave the exchangers at a temperature of from 60° to 100° F. In the modifications involving split or sectional exchangers, e. g., the modifications of 60 Figures 1, 3 and 4, the oxygen leaves exchanger 10b of Figure 1, nitrogen leaves regenerator sections 98 and 101 of Figure 3 and oxygen leaves the exchanger sections 149 and 158 of Figure 4 at a temperature of from about -120° to -175° F. and the nitrogen leaves exchanger 10b of Figure 1, regenerator section 92 or 95 of Figure 3 and exchanger section 149 of Figure 4 at a temperature of from about -120° to -175° F. The high pressure stage of the rectification system is 65 maintained at about 60 to 100 pounds and the low pressure stage at about 5 to 12 pounds. The several streams suffer only a small pressure drop in flowing through the exchangers.

It is generally advisable to recirculate a volume 70 of gasous rectification product through at least

the colder end of the exchangers corresponding to from about 10% to about 25% of the volume of the air entering the process, all volumes being measured at standard conditions.

Operating in accordance with this invention it is found that substantially complete removal of carbon dioxide takes place from the air stream prior to its introduction into the rectification system permitting efficient rectification of the air to produce oxygen and the air flow paths upon each reversal are purged to remove therefrom the carbon dioxide and frost, if any, thereby permitting continuous operation; this purging being accomplished more efficiently and at the same time a rectification product stream instrumental in improving the efficiency of the purging is withdrawn as product uncontaminated by condensibles removed from the air.

The expressions "reversing the flow of air and nitrogen or of air and oxygen" and "reversal" are used herein in the sense commonly employed in this art, namely, to mean the switching of the flow of two streams, for example, the air and the nitrogen or oxygen streams, so that upon each "reversal" the air flows through the path through which had previously flowed the nitrogen or oxygen and the nitrogen or oxygen flows through the path through which had previously flowed the air. The term "path" is used herein in a comprehensive sense to include the flow arrangement of Figure 3 in which the non-reversing recirculating nitrogen stream flows through a path consisting of four sections in parallel as well as paths consisting of sections in series as shown, for example, in Figure 1.

Since certain changes may be made in carrying out the above processes without departing from the scope of the invention, it is intended that all matter contained in the above description shall be interpreted as illustrative and not in a limiting sense. Thus, for example, instead of recirculating oxygen or nitrogen rectification products, other rectification products such as argon, neon, krypton or welding grade oxygen, may be recirculated through at least the cold end of the exchangers and the recirculated stream of such additional rectification product employed to improve the purging and still permit the withdrawal of the additional rectification product uncontaminated with condensibles removed from the air. This application contains claims generic to such operation; my copending application Serial No. 783,552 filed November 1, 1947, now Patent No. 2,513,306 of July 4, 1950, discloses and claims the modification involving the recirculation of an additional rectification product stream.

What is claimed is:

1. A process for producing oxygen by the liquefaction and rectification of air, which comprises passing a stream of rectification product through a path in a heat exchange zone, passing a stream of air through another path in said heat exchange zone, cooling the air to a temperature close to its condensation point at the pressure prevailing in the air flow path in said heat exchange zone and effecting substantially complete removal of carbon dioxide from the air in its passage through said heat exchange zone, subjecting the thus cooled air to rectification to produce said rectification product stream, periodically reversing the flow of the air stream and the said rectification product stream through their respective flow paths in said zone, passing a second stream of rectification product through

a path extending through at least the colder end of said heat exchange zone in heat exchange relation with the air and the first-mentioned stream of rectification product passing therethrough, recirculating a portion of said second stream of rectification product leaving said last-mentioned path through said last-mentioned path, and withdrawing a portion of the recirculated stream of rectification product as product uncontaminated by carbon dioxide removed from the air stream.

2. The process of claim 1 wherein the first-mentioned stream of rectification product is predominantly nitrogen and the second stream of rectification product is predominantly oxygen.

3. A process for producing oxygen by the liquefaction and rectification of air in a rectification system involving high and low pressure stages, which comprises passing a stream of rectification product through a path in a heat exchange zone, passing a stream of air through another path in said heat exchange zone, cooling the air to a temperature close to its condensation point at the pressure prevailing in the air flow path in said heat exchange zone and effecting the substantially complete removal of carbon dioxide from the air in its passage through said heat exchange zone, dividing the air stream into major and minor portions, passing the major portion to the high pressure stage of the rectification system, passing a second stream of rectification product through at least the colder end of said heat exchange zone in indirect heat exchange relation with the air and said first-mentioned rectification product stream, thereby warming said second stream of rectification product, passing the thus warmed stream of rectification product in indirect heat exchange relation with (1) at least a part of said minor portion of the air stream, thereby warming said minor portion to a temperature such that said minor portion can thereafter be expanded without substantial liquefaction, and (2) at least a portion of the first-mentioned rectification product stream prior to its entry into said heat exchange zone, thereby warming said rectification product stream to a temperature within 5° to 10° F. of the temperature of the air stream leaving said heat exchange zone, expanding said warmed minor portion of the air to produce refrigeration in amount sufficient to compensate for cold losses resulting from the difference in enthalpy between the incoming air and the outgoing products of rectification and for heat leaks into the process and introducing the expanded air into the low pressure stage of the rectification system, and periodically reversing the flows of the air and the first-mentioned rectification product stream through their respective paths in said zone, whereby upon each of said reversals the first-mentioned stream of rectification product substantially completely removes the carbon dioxide deposited in said zone during the preceding step of the process.

4. A process for producing oxygen by the liquefaction and rectification of air in a rectification system involving a high pressure stage maintained at a pressure of 60 to 100 pounds and a low pressure stage maintained at a pressure of from 5 to 12 pounds, which comprises passing a stream of rectification product from the low pressure stage through a path in a heat exchange zone, passing a stream of air at a temperature of from 70° to 110° F. and a pressure of 60 to 100 pounds

through another path in said heat exchange zone, cooling the air to a temperature close to its condensation point at the pressure prevailing in said air flow path in said heat exchange zone and effecting the substantially complete removal of carbon dioxide from the air in its passage through its flow path, introducing the thus cooled air to the high pressure stage of said rectification system, periodically reversing the flows of the air and the said rectification product through their respective paths in said zone, passing a second stream of rectification product from the rectification system through a path extending through at least the colder end of said heat exchange zone in indirect heat exchange relation with the air stream and the first-mentioned rectification product stream passing therethrough, recirculating a portion of said second stream of rectification product leaving said last-mentioned path through said last-mentioned path, and withdrawing a portion of the recirculated stream of rectification product as product uncontaminated by carbon dioxide removed from the air stream.

5. A process for producing oxygen by the liquefaction and rectification of air in a rectification system involving a high pressure stage maintained at a pressure of from 60 to 100 pounds and a low pressure stage maintained at a pressure of from 5 to 12 pounds, which comprises passing a stream of nitrogen rectification product from the low pressure stage through a path in a heat exchange zone and passing a stream of air at a pressure of from 60 to 100 pounds at a temperature of from 70° to 110° F. into and through another path in said heat exchange zone, cooling the air to a temperature close to its condensation point at the pressure prevailing in its flow path through said heat exchange zone and effecting the substantially complete removal of carbon dioxide from the air in its passage through said heat exchange zone, dividing the air stream into major and minor portions, passing the major portion to the high pressure stage of the rectification system, passing a stream of oxygen rectification product from the low pressure stage through a path extending through at least the colder end of said heat exchange zone in indirect heat exchange relation with the air and nitrogen rectification product stream passing therethrough, thereby warming said oxygen rectification product stream, passing the thus warmed oxygen rectification product stream in indirect heat exchange relation with (1) at least a part of said minor portion of the air stream thereby warming said minor portion to a temperature such that said minor portion can thereafter be expanded without substantial liquefaction, and (2) at least a part of the nitrogen rectification product stream prior to its entry into said heat exchange zone, thereby warming said nitrogen stream to a temperature within 5° to 10° F. of the temperature of the air stream leaving said heat exchange zone, expanding said warmed minor portion of the air to produce refrigeration in amount sufficient to compensate for cold losses resulting from the difference in enthalpy between the incoming air and the outgoing products of rectification and for heat leaks into the process, introducing the expanded air into said low pressure stage, periodically reversing the flows of the air and the said nitrogen rectification product stream through their respective paths in said zone, whereby upon each of said reversals the nitrogen rectification product

stream substantially completely removes the carbon dioxide deposited in said zone during the preceding step of the process, and withdrawing a portion of the said oxygen rectification product stream as product uncontaminated by condensibles removed from the air stream.

6. The process for producing oxygen by the liquefaction and rectification of air, which comprises passing a stream of nitrogen rectification product through a path in a heat exchange zone, passing a stream of air through another path in said heat exchange zone countercurrent to the direction of flow of said nitrogen stream, cooling the air to a temperature close to its condensation point at the pressure prevailing in its flow path through said heat exchange zone and effecting the substantially complete removal of carbon dioxide from the air in its passage through said heat exchange zone, periodically reversing the flows of the air and nitrogen rectification product streams through their respective paths in said zone, introducing the thus cooled air into a rectification system, passing a second stream of rectification product through a path in said heat exchange zone in a direction cocurrent with the flow of said nitrogen stream and countercurrent to the flow of said air stream, at a point in the flow of said second stream of rectification product where its temperature is within the range of -120° to -175° F., withdrawing a portion of said second stream of rectification product and recirculating the portion thus withdrawn through the path through which the second stream of rectification product flows through said heat exchange zone, and removing the remainder of said second stream of rectification product from the exit end of its flow path as product uncontaminated by condensibles removed from the air stream.

7. The process for producing oxygen by the liquefaction and rectification of air, which comprises passing a stream of nitrogen rectification product through a path in a heat exchange zone, passing a stream of air through another path in said heat exchange zone countercurrent to the direction of flow of said nitrogen stream, cooling the air to a temperature close to its condensation point at the pressure prevailing in its flow path through said heat exchange zone and effecting the substantially complete removal of carbon dioxide from the air in its passage through said heat exchange zone, periodically reversing the flows of the air and nitrogen rectification product streams through their respective paths in said zone, introducing the thus cooled air into a rectification system, passing a stream of oxygen rectification product through a path in said heat exchange zone in a direction cocurrent with the flow of said nitrogen stream and countercurrent to the flow of said air stream, at a point in said oxygen flow stream path where the temperature of the oxygen is within the range of -120° to -175° F. withdrawing a portion of the oxygen, recirculating the portion of oxygen thus withdrawn through the same path through which the oxygen rectification product stream has passed in said heat exchange zone, and removing the remainder of the oxygen rectification product stream from the exit end of its flow path as product uncontaminated by condensibles removed from the air stream.

8. The process for producing oxygen by the liquefaction and rectification of air in a rectification system involving high and low pressure stages, which comprises passing a stream of

nitrogen rectification product through a path in a heat exchange zone, passing a stream of air through another path in said heat exchange zone countercurrent to the direction of flow of said nitrogen stream, cooling the air to a temperature close to its condensation point at the pressure prevailing in its flow path through said heat exchange zone and effecting the substantially complete removal of carbon dioxide from the air in its passage through said heat exchange zone, dividing the air stream into major and minor portions, passing the major portion to the high pressure stage of the rectification system, passing a second stream of rectification product through a path extending through at least the colder end of said heat exchange zone in indirect heat exchange relation with the air and said first-mentioned rectification product stream, thereby warming said second stream of rectification product at a point in the flow of the second stream of rectification product where its temperature is within the range of -120° to -175° F., withdrawing a portion of the second rectification product and recirculating the portion thus withdrawn through the said path through which the second rectification product stream flows through said heat exchange zone, removing the remainder of the second rectification product stream from the exit end of its flow path as product uncontaminated by condensables removed from the air stream, passing the recirculated portion of the said second stream of rectification product in indirect heat exchange relation with (1) at least a part of said minor portion of the air stream, thereby warming said minor portion to a temperature such that said minor portion can thereafter be expanded without substantial liquefaction and (2) at least a part of the first-mentioned rectification product stream prior to its entry into said heat exchange zone, thereby warming said rectification product stream to a temperature within 5° to 10° F. of the temperature of the air stream leaving said heat exchange zone, expanding said warmed minor portion of the air to produce refrigeration in amount sufficient to compensate for cold losses resulting from the difference in enthalpy between the incoming air and the outgoing products of rectification and for heat leaks into the process, introducing the expanded air into the low pressure stage of the rectification system, and periodically reversing the flows of the air and nitrogen rectification product streams through their respective paths in said zone.

9. The process for producing oxygen by the liquefaction and rectification of air in a rectification system involving a high pressure stage maintained at a pressure of from 60 to 100 pounds and a low pressure stage maintained at a pressure of from 5 to 12 pounds, which comprises passing a stream of nitrogen rectification product from the low pressure stage through a path in a heat exchange zone, passing a stream of air at a pressure of from 60 to 100 pounds at a temperature of from 70° to 110° F. through another path in said heat exchange zone countercurrent to the direction of flow of said nitrogen stream, cooling the air to a temperature close to its condensation point at the pressure prevailing in its flow path through said heat exchange zone and effecting the substantially complete removal of carbon dioxide from the air in its passage through said heat exchange zone, dividing the air stream into major and minor portions, passing the major portion to the high pressure stage of the rectification

system, passing a stream of oxygen rectification product from the said low pressure stage through a path extending through at least the colder end of said heat exchange zone in indirect heat exchange relation with the air and said nitrogen rectification product stream, thereby warming said oxygen stream of rectification product at a point in said oxygen flow stream path where the temperature of the oxygen is within the range of -120° to -175° F., withdrawing a portion of the oxygen and recirculating the portion thus withdrawn through the said path through which the oxygen rectification product stream flows through said heat exchange zone, removing the remainder of the oxygen rectification product stream from the exit end of its flow path as product uncontaminated by condensables removed from the air stream, passing the recirculated portion of said stream of oxygen in indirect heat exchange relation with (1) at least a part of said minor portion of the air stream, thereby warming said minor portion to a temperature such that said minor portion can thereafter be expanded without substantial liquefaction and (2) at least a part of the nitrogen rectification product stream prior to its entry into said heat exchange zone, thereby warming said nitrogen rectification product stream to a temperature within 5° to 10° F. of the temperature of the air stream leaving said heat exchange zone, expanding said warmed minor portion of the air to a pressure of from 5 to 12 pounds, thereby producing refrigeration in amount sufficient to compensate for cold losses resulting from the difference in enthalpy between the incoming air and the outgoing products of rectification and for heat leaks into the process, introducing the expanded air into the low pressure stage of the rectification system, and periodically reversing the flows of the air and nitrogen rectification product streams through their respective paths in said zone.

10. A process for producing oxygen by the liquefaction and rectification of air, which comprises passing a stream of rectification product through one of a pair of regenerators while simultaneously passing through the other of said regenerators a stream of air, periodically reversing the flow of said air stream and rectification product stream through the regenerators of said pair, whereby said air stream recovers the cold content of the rectification product stream, is cooled to a temperature close to its condensation point at the pressure prevailing in its flow through said regenerator, carbon dioxide is substantially completely removed from the air stream in its flow through said regenerators and the rectification product stream substantially completely removes the carbon dioxide deposited in the regenerator through which the air flows during the preceding step of the process, introducing the thus cooled air into the rectification system, passing a second stream of rectification product through at least the cold ends of said regenerators in indirect heat exchange relation with the gaseous media passing therethrough, withdrawing a portion of the second-mentioned stream of rectification product as product uncontaminated by condensables removed from the air stream, and recirculating the remainder of said second stream of rectification product through its flow path in said regenerators.

11. A process for producing oxygen by the liquefaction and rectification of air, which comprises passing a stream of nitrogen rectification product through one of a pair of regenerators while simultaneously passing through the other of said

regenerators a stream of air, periodically reversing the flow of said air stream and nitrogen rectification product stream through the regenerators of said pair whereby the air stream recovers the cold content of the nitrogen rectification product stream, is cooled to a temperature close to its condensation point at the pressure prevailing in its flow through said regenerator, carbon dioxide is substantially completely removed from said air stream in its flow through said regenerators and the nitrogen rectification product stream substantially completely removes the carbon dioxide deposited in the regenerator through which the air flows during the preceding step of the process, introducing the thus cooled air into the rectification system, passing a stream of oxygen rectification product through at least the cold ends of said regenerators in indirect heat exchange relation with the nitrogen and air passing therethrough, the oxygen flowing cocurrently with the nitrogen stream and countercurrent to the direction of flow of the air stream, withdrawing a portion of the oxygen stream as product uncontaminated by condensables removed from the air stream, and recirculating the remainder of the oxygen stream through its flow path in at least the cold ends of said regenerators.

12. A process for producing oxygen by the liquefaction and rectification of air, which comprises passing a stream of nitrogen rectification product through one of a pair of regenerators while simultaneously passing through the other of said regenerators a stream of air, periodically reversing the flow of said air stream and nitrogen rectification product stream through the regenerators of said pair whereby the air stream recovers the cold content of the nitrogen rectification product stream, is cooled to a temperature close to its condensation point at the pressure prevailing in its flow through said regenerator, carbon dioxide is substantially completely removed from said air stream in its flow through said regenerators and the nitrogen rectification product stream substantially completely removes the carbon dioxide deposited in the regenerator through which the air flows during the preceding step of the process, introducing the thus cooled air into the rectification system, passing a stream of oxygen rectification product through said regenerators in indirect heat exchange relation with the nitrogen and air passing therethrough, withdrawing a portion of the oxygen stream as product uncontaminated by condensables removed from the air stream, and recirculating the remainder of the oxygen stream through its flow path in said regenerators.

13. A process for producing oxygen by the liquefaction and rectification of air, which comprises passing a stream of nitrogen rectification product through one of a pair of regenerators while simultaneously passing a stream of air through the other of said regenerators, passing a stream of oxygen rectification product through one of a second pair of regenerators while simultaneously passing air through the other of said pair of regenerators, periodically reversing the flow of nitrogen and air through the respective regenerators of the first-mentioned pair and the flow of oxygen and air through the respective regenerators of the second-mentioned pair, cooling the air passing through said regenerators to a temperature close to its condensation point at the pressure prevailing in its flow through said regenerators, effecting the substantially complete removal of carbon dioxide from the air in its pas-

sage through said regenerators, and effecting substantially complete removal of the carbon dioxide deposited in the regenerators, and recirculating a stream of rectification product through at least the colder ends of all of said regenerators in indirect heat exchange relation with the gaseous media passing therethrough.

14. A process for producing oxygen by the liquefaction and rectification of air, which comprises passing a stream of nitrogen rectification product through one of a pair of regenerators while simultaneously passing a stream of air through the other of said regenerators, passing a stream of oxygen rectification product through one of a second pair of regenerators while simultaneously passing air through the other of said pair of regenerators, periodically reversing the flow of nitrogen and air through the respective regenerators of the first-mentioned pair and the flow of oxygen and air through the respective regenerators of the second-mentioned pair, cooling the air passing through said regenerators to a temperature close to its condensation point at the pressure prevailing in its flow paths in said regenerators through which the air flows, effecting the substantially complete removal of carbon dioxide from the air in its passage through said regenerators and effecting substantially complete removal of the carbon dioxide deposited in the regenerators, recirculating a stream of nitrogen rectification product through at least the colder ends of all of said regenerators in indirect heat exchange relation with the gaseous media passing therethrough, and withdrawing a portion of the recirculating stream of nitrogen rectification product uncontaminated by condensables removed from the air stream.

15. A process for producing oxygen by the liquefaction and rectification of air, which comprises passing a stream of nitrogen rectification product through one of a pair of regenerators while simultaneously passing a stream of air through the other of said regenerators, recirculating a stream of oxygen rectification product through at least the colder ends of said pair of regenerators in indirect heat exchange relation with the gaseous media passing therethrough, periodically reversing the flow of nitrogen and air through their respective regenerators, cooling the air passing through said regenerators to a temperature close to its condensation point at the pressure prevailing in its flow paths through said regenerators when the air flows therethrough, effecting the substantially complete removal of carbon dioxide from the air in its passage through said regenerators and effecting substantially complete removal of the carbon dioxide deposited in the regenerators by the nitrogen rectification product stream passing therethrough, and withdrawing a portion of the recirculating oxygen stream uncontaminated by condensables removed from the air stream.

16. A process for producing oxygen by the liquefaction and rectification of air, which comprises passing a stream of nitrogen rectification product through a path in a heat exchange zone, passing a stream of air through another path in said heat exchange zone to recover the cold content of the nitrogen rectification product stream, cooling the air to a temperature close to its condensation point at the pressure prevailing in the air flow path in said heat exchange zone and effecting substantially complete removal of carbon dioxide from the air in its passage through

said heat exchange zone, passing a stream of oxygen rectification product through a path in a second heat exchange zone, passing a stream of air through another path in said second heat exchange zone to recover the cold content of the oxygen rectification product stream, cooling the air to a temperature close to its condensation point at the pressure prevailing in the air flow path in said second heat exchange zone and effecting substantially complete removal of carbon dioxide from the air in its passage through said second heat exchange zone, passing a second stream of oxygen rectification product in two parts, respectively, through a unidirectional flow path in at least the colder end of the first-mentioned heat exchange zone and a unidirectional flow path in at least the colder end of said second heat exchange zone, thus warming said second oxygen stream, passing the thus warmed second oxygen stream in indirect heat exchange relation with the stream of nitrogen supplied to the first-mentioned heat exchange zone, thereby cooling said warmed second oxygen stream, recirculating the thus cooled second oxygen stream in two parts, respectively, through said unidirectional flow paths, periodically reversing the flow of air and nitrogen through their respective paths in the first-mentioned heat exchange zone and the flow of air and oxygen through their respective paths in said second heat exchange zone, and withdrawing a portion of said second oxygen stream as product uncontaminated by condensibles removed from the air streams.

17. A process for producing oxygen by the liquefaction and rectification of air, which comprises passing a first stream of rectification product through a path in each of two heat exchange zones arranged in parallel, passing a second stream of air through another path in each of said two heat exchange zones, thereby cooling the air to a temperature close to its condensation point at the pressure prevailing in the air flow paths in said two heat exchange zones and effecting substantially complete removal of carbon dioxide from the air in its passage through said two heat exchange zones, passing a third stream of rectification product through a unidirectional flow path in at least the colder end of each of said two heat exchange zones, thus warming said third stream of rectification product, recirculating a portion of the warmed third stream of rectification product through said unidirectional flow path of at least one of said two heat exchange zones, periodically reversing the flow of air and said first stream of rectification product through their respective paths in each of said two heat exchange zones, and withdrawing a portion of the warmed third stream of rectification product as product uncontaminated by carbon dioxide re-

moved from the air in said two heat exchange zones.

18. A process for producing oxygen by the liquefaction and rectification of air, which comprises passing a first stream of rectification product through a path in each of two heat exchange zones arranged in parallel, passing a second stream of air through another path in each of said two heat exchange zones, thereby cooling the air to a temperature close to its condensation point at the pressure prevailing in the air flow paths in said two heat exchange zones and effecting substantially complete removal of carbon dioxide from the air in its passage through said two heat exchange zones, passing a third stream of rectification product through a unidirectional flow path in at least the colder end of each of said two heat exchange zones, thus warming said third stream of rectification product, cooling a portion of the warmed third stream of rectification product, recirculating the cooled portion through said unidirectional flow path of at least one of said two heat exchange zones, periodically reversing the flow of air and said first stream of rectification product through their respective paths in each of said two heat exchange zones, and withdrawing a portion of the warmed third stream of rectification product as product uncontaminated by carbon dioxide removed from the air in said two heat exchange zones.

19. The process of claim 18 wherein the cooling of a portion of the warmed third stream of rectification product is effected by passing said warmed portion in heat exchange relation with the first stream of rectification product flowing to one of said two heat exchange zones.
